UNITED STATES PATENT OFFICE.

ERNST THEODOR LIPPERT, OF PITTSBURG, PENNSYLVANIA.

INSERTIBLE SAW-TOOTH.

SPECIFICATION forming part of Letters Patent No. 317,656, dated May 12, 1885.

Application filed February 2, 1885. (No model.)

To all whom it may concern:

Be it known that I, ERNST T. LIPPERT, a citizen of the United States, residing at Pittsburgh, in the county of Allegheny and State of Pennsylvania, have invented certain new and useful Improvements in Saw-Teeth; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to insertible saw-teeth, the object being to secure a saw-tooth by a combined wedge and clamping action, as herein-after fully described.

The invention consists in the features of construction hereinafter fully described, and pointed out in the claims.

In the drawings, Figure 1 illustrates a plan view of my improvement. Fig. 2 is a vertical, and Fig. 3 a longitudinal sectional, view of the same.

A represents a portion of the body of a saw formed with the usual recess to receive the heel B, which latter is grooved to fit the convex edges a of the recess. The heel B is formed with a recess, C, to receive the removable tooth D, and with an extended slot, E, which terminates in a round opening, F.

G represents a wedge formed convex on one side to enter the adjacent grooved edge of the heel, and grooved at its opposite side to engage the adjacent convex edge of the saw-recess.

It will be apparent that when the wedge is driven tightly in place it will have the effect not only of securing the heel in place, but also of clamping the tooth firmly between the walls 40 of its slotted seat, as the heel is made of superior steel, possessing considerable elasticity.

The devices thus described permit the ready removal and renewal of the tooth when necessary.

I am aware that in this class of inventions it is not new, broadly, to employ a slotted heel in the recess of a saw-body and to employ a wedge for causing the saw-tooth to become tightly clamped between the sides of said recess; but I am not aware that the specific construction and combination of parts herein claimed have ever before been devised.

Having fully described my invention, what I claim as new, and desire to secure by Letters 55 Patent, is—

The combination, with a saw-body having recess therein provided with convex edges, of the heel having grooved edges and formed with a recess to receive the removable tooth and 60 with an extended slot terminating in a round opening, and a wedge formed convex on one side to enter the adjacent grooved edge of the heel, and grooved at its opposite side to engage the convex edge of the saw-recess, all substantially as shown and described.

In testimony whereof I affix my signature in presence of two witnesses.

ERNST THEODOR LIPPERT.
